L. AZARRAGA

METHOD OF NIGHT AERIAL ADVERTISING

Filed Dec. 21, 1926

FIG. 1.

FIG. 2.

FIG. 3.

INVENTOR
LUIS AZARRAGA.
BY *W. Shaeff Jr.*
ATTORNEY

UNITED STATES PATENT OFFICE.

LUIS AZARRAGA, OF HEMPSTEAD, NEW YORK.

METHOD OF NIGHT AERIAL ADVERTISING.

Application filed December 21, 1926. Serial No. 156,117.

My invention relates to advertising devices of the character described in application Serial Number 156,118 filed concurrently herewith and is more particularly concerned with a means and method of aerial advertising at night.

An object of the invention is to provide a sign or the like which is adapted to be supported aloft by means of a captive balloon or other lighter-than-air-craft and which, regardless of the movement of the balloon thru space, is continuously illuminated by means of a projected light.

A further object of the invention is to mount the light projecting apparatus as to admit of its free swinging movement in any direction, and to couple therewith the balloon or other lighter-than-air-craft in a manner such that the movement of the balloon, and hence the sign, is properly coordinated with the swinging movement of said apparatus.

A still further object of the invention is to provide a night aerial advertising device which is economical in operation, which is more or less startling in its appeal, and which, if displayed aloft over thickly populated centers, will be visible to and readable by a maximum number of observers.

Other objects and advantages of the invention will be hereinafter set forth.

In the drawings, wherein like reference characters denote like or corresponding parts,

Fig. 1 is a side elevation of the device, the dotted lines indicating the manner in which the light rays automatically follow the sign,

Fig. 2 is a detail view of the mounting for the light projecting apparatus, and

Fig. 3 is a transverse vertical sectional view of the sign receiving surface.

In the embodiment of the invention selected for illustration, a more or less conventional form of non-rigid captive balloon 10 is shown as a means for raising and holding the sign aloft. From said balloon 10 a plurality of converging lines 10' are hung. These lines 10' are preferably fastened to a ring 10² to which is attached the outer or upper end of the tether line 11. The tether line, at or near its point of attachment to the balloon ring 10² is divided to receive between the separate line portions a substantially ball shaped member 11'. Said ball member 11', for the convenient attachment

of said line portions, has formed thereon, at diametrically opposite points, two eye-extensions 11² and 11³, the former extending in an upward direction and the latter extending oppositely.

In Fig. 3, wherein is illustrated the simplest form of my invention, the ball member 11', except for the eye-extensions 11² and 11³, is substantially spherical, altho it may, if desired, be out-of-round on its undersurface. The function of said ball member is that of a ball shaped support for the sign structure designated in its entirety as 12. Said sign structure is preferably of light construction, circular, and substantially horizontally flat. It comprises, as herein illustrated, a marginal frame piece 12' of bamboo or other light strong material, a center frame piece 12² of aluminum or an aluminum alloy, and a netting or silken web 12³ which may or may not be reinforced. The center frame piece 12², unlike the marginal frame piece 12', is substantially socket shaped. At its exact center it has formed therein an opening 12⁴ thru which the tether line 11 extends. The inner socket wall of said frame piece 12² is preferably substantially complementary to the top rounded outer surface of the ball 11' which is adapted to loosely engage therewith. Such engagement provides, in effect, a ball and socket joint between the tether line 11 and the sign. Thus supported, the sign is free to either rotate or tilt laterally in the wind.

The means employed for tilting or rotating the sign structure 12 relatively to the tether line 11, comprises a vertical fin surface 13 and a horizontal fin surface 13'. Said fin surfaces are both carried by the framing 12' at one side of its point of support adjacent to the margin of the sign. Both surfaces function as stabilizing surfaces which tend to hold the sign at all times substantially horizontal and parallel to the earth's surface regardless of the changing angular position of the tether line. The vertical fin surface 13 is preferably mounted on the top side of the sign receiving surface so as to be hidden thereby when viewed from beneath, whereas the horizontal fin surface 13' is preferably formed by closing a portion of the web 12³ against the passage of air therethru. To counter-balance the weight of said fin surfaces, the opposed sign portion may be slightly weighted as indicated at 13².

The tether line 11, instead of being fastened at its inner end to a windlass or the like, is firmly fastened as at 14 to a light projecting apparatus designated in its entirety as 15. This light projecting apparatus 15 is so mounted on or within a suitable stand or base 16 as to admit of its free swinging movement in any direction. The character of light projecting apparatus employed, however, is immaterial. If the sign receiving surface 12 is constructed in the form of a picture screen, a picture projecting apparatus can be used to project thereon either a picture, letters, figures, or other advertising intelligence. If, on the other hand, the sign receiving surface is merely a sheet surface having permanently delineated thereon the advertising intelligence, then, if desired, the light projecting apparatus can partake of the form of a high powered or concentrated spot light. In any event, it is necessary that the projected light be directed onto the sign receiving surface, and that said sign receiving surface shall have depicted thereon the advertising intelligence intended for display.

An advertising device of the character mentioned is especially desirable in view of its strong aesthetic appeal. Not only is the beam or shaft of light attractive and conspicuous, but the unobstructed movement of the sign thru space, due to the free float-

ing of the balloon in the wind, immediately draws attention to the sign. Of a special importance, however, is the direct attachment of the tether line to the light projecting apparatus since it is this connection alone which provides for that coordinated movement between the light and balloon so essential to the successful practice of the invention. Moreover, by reason of the method and means employed, the sign, when once in operation, and the light rays properly focused, requires no further attention, either manual or otherwise, for an indefinite display.

What is claimed therefore is:

In a night aerial advertising sign or the like, the combination, of an apparatus for projecting light, a stand upon which said apparatus is mounted for free swinging movement in any direction, a captive balloon, a tether line for said balloon fastened at one end to said apparatus, a relatively flat structure affording a sign receiving surface suspended from said tether line and onto which the projected light is adapted to be continuously directed, and means for holding said structure in a substantially horizontally flat position regardless of the angularity of said tether line.

In testimony whereof I hereunto affix my signature.

LUIS AZARRAGA.
